[57] CLAIM

The ornamental design for a corner lighting fixture, as shown and described.

DESCRIPTION

FIG. 1 is a top front perspective view of a corner lighting fixture showing my new design;

FIG. 2 is a right side elevation thereof.

FIG. 3 is a top plan view thereof.

FIG. 4 is a bottom plan view thereof.

FIG. 5 is a left side elevation view thereof.

FIG. 6 is a rear elevation view thereof.

The interior lamps and brackets are shown in broken lines in FIGS. 1, 3 and 4 for illustrative purposes only.

FIG. 1.

FIG. 3.

FIG. 2.

FIG. 4.
